UNITED STATES PATENT OFFICE.

CHARLES E. WAREAM, OF CINCINNATI, OHIO, ASSIGNOR, BY DIRECT AND MESNE ASSIGNMENTS, OF ONE-HALF TO THE AMERICAN LAUNDRY MACHINERY COMPANY, OF NORWOOD, OHIO, A CORPORATION OF OHIO, AND ONE-HALF TO METROPOLITAN TRUST COMPANY, TRUSTEE, OF NEW YORK, N. Y., A CORPORATION OF NEW YORK.

GARMENT PRESS.

Application filed June 19, 1920. Serial No. 390,229.

To all whom it may concern:

Be it known that I, CHARLES E. WAREAM, a citizen of the United States, residing at Cincinnati, in the county of Hamilton and 5 State of Ohio, have invented certain new and useful Improvements in Garment Presses, of which the following is a specification.

This invention relates to the class of 10 laundry machines and more particularly to improvements in garment presses.

The object of the invention is to provide an improved means for distributing air through the buck or garment supporting 15 member to dispel the live steam therefrom as well as from the garment upon completion of the pressing operation.

Other objects of the invention will appear 20 from the following description and claims when considered in connection with the accompanying drawings.

Fig. 1 is a front elevation of my machine; Fig. 2 is an end elevation thereof; Fig. 3 is a vertical longitudinal section of 25 the buck or garment supporting member; Fig. 4 is a transverse vertical section taken on line *a—a*, Fig. 3; and Fig. 5 is a plan view of the buck with parts broken away.

The frame 1 supports the work table 2 30 and the buck or garment supporting member 3, while the presser head 4 is pivotally mounted upon the front end of the overhanging arm 5. The arm 5 is swivelly mounted at 6 upon the upper end of an arm 35 of the main frame 1 and carries a counter-weight 7 at its rear end. The spring 8 which extends between the overhanging arm 5 and the base portion of the frame 1 normally tends to hold the presser head in open 40 position away from the buck. The presser head is closed by means of treadle 10 which operates the toggle lever mechanism through the lever connections 11 and 12. The bell crank lever 12 is pivotally mounted at 13 45 upon the frame of the machine and has pivotal connection at 14 with the lever members 15 which are connected at 16 with the other parts of the toggle lever mechanism.

The toggle lever comprises the connecting 50 link 17 which is pivotally connected to the base of the frame, and the rod 18 which has pivotal connection at 20 with the overhang-

ing arm 5. The rod 18 can be adjusted so as to lengthen or shorten the throw of this toggle lever. This last feature is fully described in the patent to Cooper 1332711 of March 2, 1920.

Adjustment of the rod 18 serves also to vary the tension upon the spring 19. Means is shown at 21 for locking the rod 18 in the 60 position in which it is adjusted. A rod 22 having pivotal connection at 23 with the link 17 has pivotal connection with the lever arms 15 and is provided with a screw threaded nut 24 which can be set at different positions so as to form a stop for limiting the movement of the toggle lever mechanism. The structure as thus far explained being 65 old in the art will not be described in any fuller detail.

The presser head is brought in closed position by means of a handle 25, and any suitable means may be provided for supplying steam thereto, as for instance through the pipe connection 26. This being an old 70 practice, it will not be described in any fuller detail.

The buck or garment supporting member which I have adopted for use with my invention comprises a plate 27 which is provided along its marginal portions with channels 28. Strips of suitable material, such as for instance as sheet metal 29, are secured along the marginal portions of the plate 27 so as to overhang these channels. These 75 strips are secured in position in any suitable manner, as for instance by means of screws 30. As will be clearly seen from Fig. 5, these strips which are narrowed towards their ends, are so arranged that their upper 80 faces are flush with the upper surface of the plate 27 and form the graduated slots 28a for the passage of steam. Superimposed upon the plate 27 are a suitable number of layers of padding 31 which are covered and 85 enclosed at their edge portions by means of oilcloth 32. The topmost layer comprises padding 33 covered by the ordinary muslin or other fabric 34 which is pervious to steam and air.

With this form of buck, the steam is uniformly distributed because of the graduated slots; and because of the oilcloth which is impervious to steam, the steam is distributed 90

through only the upper layer of padding. The form of buck as thus far described is practically the same as that covered by the application of B. W. Brockett filed June 5 1920, Serial Number 390,170.

The buck is provided with a steam chamber 36 having communication through the pipe 37 with the steam supply. A drain 38 is also provided for the condensed steam. An extension 39 from the underside of the plate member 27 provides a channel 40 which extends transversely across the buck and terminates at its ends in the restricted ducts 40 which, as will be seen from Fig. 4, are 10 in communication with the channels 28. Communication is had between the steam chest 36 and the channel 40 through the ports 41 and 42 which are under control of the valve 43. This valve is actuated by 15 means of the rod 44 which extends out through the lower wall of the buck and is enclosed by the casing 45. As will be seen from Fig. 2, the valve rod 44 is actuated by 20 means of treadle 46.

25 The feature which forms the specific subject matter of this application is the means for equalizing the distribution of air which involves the flattened tube now to be referred to. As seen in Fig. 4, a depression 30 is formed along the middle portion of the lower layers of padding on the buck to accomodate the flattened tubular member 35 which is provided with apertures 36 along its side edges. Thus the upper surface of 35 the flattened tubular member is flush with the upper surface of oilcloth 32 and the sides of this depression are inclined so as to deflect the air to the upper padding. The function of this tube is to distribute the air 40 through the padding so as to more efficiently remove the steam therefrom, upon completion of the pressing operation. This tubular member maybe made of any suitable material, as for instance light metal, and is 45 preferably located in the upper part of the padding, as shown in the drawings.

An air fan 47 has pipe connection as indicated at 48 and 49 with the end portions of the tubular member 35. The valve 46 50 which is normally in closed position as indicated in Fig. 3 is actuated by means of rod 47 which is in turn actuated by treadle 49. As will be seen from Fig. 2, pressure upon treadle 49 will operate the lever connections 50 and 51 and the bell crank lever 52 which is mounted upon shaft 53 supported in suitable bearings 54 on the frame. One end of the lever 52 has a forked arm 55 which engages a spring 56 arranged below 55 the collar 57 on valve rod 58. A stop or rest 59 is provided on the end of treadle lever 49 for engaging the floor.

60 Thus, it will be seen from the foregoing description that upon bringing the presser head in closed relation with the buck, steam

can be supplied to either or both of the ironing members by means of the steam connections referred to, and upon completion of the pressing operation a current of air can be turned into the flattened tubular member 70 for the purpose of dispelling the steam from the padding of the buck and also from the garment.

The current of air upon being supplied to the two ends of the flattened tube 35 will 75 pass through the tube toward the middle portion of the buck, and will be allowed to be distributed out through the apertures. The result of this arrangement is that a more uniform distribution of air is obtained 80 through the padding and hence the steam can be more quickly dispelled from the padding and while still in the mobile state. The advantage of this arrangement is that the padding will not be permitted to become soggy, and consequently the life of the padding will be prolonged.

85 Other advantages resulting from this invention will suggest themselves to those who are familiar with the art to which it relates.

90 What I claim is:

1. In a garment press, a garment support having an imperforate upper plate and a heating chamber beneath the same, padding resting on said plate, and a conduit extending through said padding to a point within the same for conducting and distributing a gaseous medium through said padding.

95 2. In a garment press, a garment support having an imperforate upper plate and a heating chamber below the same, padding on said plate and having a lower portion impervious to a gaseous medium and an upper portion pervious thereto, and a conduit extending from the margin of said garment support into said padding for conducting a gaseous medium to and distributing it through the pervious upper layer thereof.

100 3. In a garment press, a garment support having an imperforate upper plate and a heating chamber below the same, padding on said plate and having a lower portion impervious to a gaseous medium and an upper portion pervious thereto, and a conduit extending from the margin of said garment support between the upper and lower portions of said padding for conducting a gaseous medium to and distributing it through the pervious upper layer thereof.

110 4. In a garment press, the combination of a garment supporting member including a support having a covering of padding that is pervious to steam and air, means for supplying steam to said padding means for supplying air to a point within the padding, said padding being provided within its thickness with a conduit having walls 115 120 130

impervious to air and communicating with said air supplying means, said conduit being provided with means for the distribution of air therefrom through the padding.

5 5. In a garment press, the combination of a garment supporting member including a support having a covering of padding that is pervious to steam and air, means for supplying steam to said padding, means for supplying air to a point within the upper part of said padding and a perforated tubular member extending from said point of air supply through the padding of said garment supporting member for distribution of air therethrough.

6. In a garment press, the combination of a garment supporting member including a support having a covering of padding that is pervious to steam and air, means for 20 supplying steam to said padding, means for supplying air to a point within the upper part of said padding and a perforated flattened tubular member extending from said point of air supply through the padding of said garment supporting member for distribution of air therethrough.

7. In a garment press, the combination of a garment supporting member having a covering of padding that is pervious to steam and air, means for supplying steam to said padding, means for supplying air to separated points in the padding, and tubular means extending between said points of air supply for distribution of air through the padding.

8. In a garment press, the combination of a garment supporting member having a covering of padding that is pervious to steam and air, means for supplying steam to said padding, means for supplying air to separated points in the padding, and flattened tubular means extending between said

points of air supply for distribution of air through the padding.

9. In a garment press, the combination of 45 a garment supporting member including a support having a covering of padding that is pervious to steam and air, means for supplying steam to said padding, means for supplying air to a point within the upper 50 part of said padding, the lower portion of the padding of said garment supporting member being formed with a depression, and means situated in said depression for distributing said air through the padding 55 of said garment supporting member.

10. In a garment press, the combination of 60 a garment supporting member including a support having a covering of padding that is pervious to steam and air, means for supplying steam to said padding, means for supplying air to a point within the upper part of said padding, the lower portion of the padding of said garment supporting member being formed with a depression, 65 and tubular means situated in said depression for distributing said air through the padding of said garment supporting member.

11. In a garment press, the combination 70 of a garment supporting member including a support having a covering of padding that is pervious to steam and air, means for supplying steam to said padding, means for supplying air to a point within the upper 75 part of said padding, the lower portion of the padding of said garment supporting member being formed with a depression, and flattened tubular means situated in said depression for distributing said air through 80 the padding of said garment supporting member.

In testimony whereof I affix my signature.
CHARLES E. WAREAM.
